AIRPLANE ENGINE

Wayne N. Morgan, Merced, Calif.

Application September 8, 1934, Serial No. 743,257

3 Claims. (Cl. 123—56)

This invention relates to internal combustion engines and particularly to a four cycle gas engine especially designed for airplane use where the weight of the engine per horse power must be kept as low as possible.

The principal object of my invention is to provide an engine for this purpose constructed in such a manner that the power of a four cylinder engine is obtained with an engine of practically 10 the same size and weight as one of two cylinders constructed in the conventional manner.

This construction involves the use of cylinders closed at both ends with a piston in each cylinder, and a means to take in and fire charges on 15 both sides of the pistons in alternating relation. The pistons therefore tend to become very hot and another object of my invention is to provide for circulating a cooling liquid through the pistons as the engine operates so that the heat will 20 be kept within reasonable limits.

The pistons are connected so as to reciprocate as a unit and a further object is to arrange the connecting means so that the heat imparted thereto from the pistons and the exploding mixture will be rapidly dissipated, not only preventing such connecting means from possibly warping but aiding in cooling the pistons themselves.

Also, the connecting means above mentioned is of such a nature that rigidity of the reciprocating unit is obtained, as well as a constant piston travel relative to crank pin travel, and most of the usual vibration is avoided.

A further object of the invention is to produce a simple and inexpensive device and yet one 35 which will be exceedingly effective for the purpose for which it is designed.

These objects I accomplish by means of such structure and relative arrangement of parts as will fully appear by a perusal of the following 40 specification and claims.

In the drawings similar characters of reference indicate corresponding parts in the several views:

Figure 1 is a sectional elevation of my improved 45 engine.

Figure 2 is an enlarged fragmentary side view partly in section of the piston and cross head unit, showing the circulating arrangement for the piston cooling medium.

Figure 3 is an enlarged cross section on the line 3—3 of Figure 1.

Referring now more particularly to the characters of reference on the drawings, the numeral 1 denotes a pair of opposed axially aligned 55 cylinders closed at their opposite outer ends by

integral heads and also at their inner ends by suitably formed abutments 2. The cylinders are rigidly connected to a crank case 3 which is disposed therebetween.

Hollow pistons 4 of drum-like form and closed on both ends are slidable in the cylinders. A slotted cross head 5 is disposed in the crank case, in the slot of which cross head slides a block 6. It is of course understood that this slot extends in a direction at right angles to the axial line 10 of the pistons. The crank pin 7 of a counterbalanced crank shaft 8 is turnable in the block, the length of the cross head slot being of course not less than the full throw of the crank.

Rods 9 parallel to the axis of the pistons are 15 secured to the cross heads and project from opposite sides of the same through the abutments and extend along and in contact with the pistons at diametrically opposed points, so that said rods are adjacent the cylinder walls. The rods 20 are secured to the pistons by transverse tie pins 10 extending therethrough (see Figure 2), said pins being relatively thick in the direction of shearing strains but thin transversely of the pistons and rods. The rods are slidable in sleeves 11 25 projecting through the abutments and extending from end to end of the cylinders, said sleeves being snugly fitted in the abutments and cylinders so that there is no leakage thereabout. In this manner while the cylinders closely surround 30 the pistons they also surround the rod sleeves as clearly shown in Figure 3.

The sleeves closely surround the rods except where they are split lengthwise for a width equal to that of the pins 10. Compression rings 12 35 about the rods engage the sleeves to prevent leakage while similar rings 13 about the pistons on both sides of the connecting pins engage the walls of the cylinders. It will thus be seen that the pistons and cross heads are of course so disposed relative to the cross head that when said cross head is at its limit of movement in one direction, one piston is adjacent the abutment of its cylinder while the other piston is adjacent the outer head of the corresponding cylinder. 45

The outer head of each cylinder has intake and exhaust valves 14 of the usual character mounted therein, while the abutments have similar transversely spaced valves, the stems 15 of which project inside the crank case. A pair of opposed cam shafts 16 driven from the crank shaft in any suitable manner extend through the crank case clear of the path of movement of the cross head. One cam shaft has cams 17 thereon which separately engage one end of bell crank rocker 50 55

arms 18. These arms at their opposite ends engage the stems 15 of the abutment intake valves, the other intake valves 14 being actuated from the same cam shaft by suitable means on the 5 outside of the crank case and engine as indicated. The various exhaust valves are similarly operated from the other cam shaft in properly timed relation to the operation of the intake valves, and since such exhaust valve arrangement would be identical with that of the intake valves it is not thought necessary to illustrate the same, since they are located on that side of the engine which is removed in the sectional elevation. The cams will of course be set 10 15 so as to obtain any desired firing order of the cylinders and the mechanism for operating the valves may be different from that shown.

In any event however it will be seen that explosive mixtures will be alternately received in 20 the cylinders on opposite sides of the pistons, so that each cylinder and piston is therefore equal to a pair of cylinders and pistons of the usual engine and space and weight are greatly conserved.

25 The pistons are thus unavoidably subjected to great heat, and while some of this heat is carried away by the rods 9 which are practically in contact with the cooled cylinder walls, it is desirable to more definitely cool the pistons. This 30 is preferably done by the following arrangement:

The crank shaft and crank pin are hollow and oil is circulated therethrough for lubricating purposes as is now commonly done with forced feed lubricating systems. Oil from the interior of the 35 crank pin feeds through a port 19 therein to a circumferential groove 20 in the block 6. This groove is in communication with the opposite edges of the block 6 by passages 21. Each passage is adapted to communicate, during a portion 40 of the stroke of the block, with the outer end of a passage 22 in the cross head which leads to the adjacent end of a passage 23 extending lengthwise through one of the rods 9 which projects from that side of the cross head. The opposite 45 end of the passage 23 communicates with a passage 24 in the corresponding tie pin 10, said passage opening into the interior of the corresponding hollow piston 4. Another passage 25 in said pin communicates with the interior of the piston 50 and also with a longitudinal passage 26 in the other rod 9, which passage 26 discharges into the crank case at the edge of the cross head slot, as shown in Figure 2.

It will therefore be seen that oil is intermittently circulated through the pistons with the operation of the engine. In this manner not only are the pistons themselves kept in a reasonably cool condition, but this cooling action is also imparted to the connecting rods through which the oil is flowing. The oil discharged into the crank case is as usual pumped back into the system, being cooled before being returned into the crank shaft as is now commonly done.

10 The engine may be mounted in position in the airplane by any suitable means, which preferably comprises a plurality of rods or tubing 27 extending parallel to the crank shaft and engaging the outside of the crank case at circumferentially 15 spaced points in cradling relation therewith and being clamped thereto, as clearly shown in Figure 1.

20 From the foregoing description it will be readily seen that I have produced such a device as substantially fulfills the objects of the invention as set forth herein.

25 While this specification sets forth in detail the present and preferred construction of the device, still in practice such deviations from such detail may be resorted to as do not form a departure from the spirit of the invention, as defined by the appended claims.

Having thus described my invention what I 30 claim as new and useful and desire to secure by Letters Patent is:

1. In a gas engine having a cylinder closed at both ends and a piston slidable in the cylinder, rods parallel to the piston disposed in contact with and secured to the peripheral face thereof at diametrically opposed points, and guide elements 35 in the cylinder about the rods, said elements and the cylinder walls following the contour of and engaging the piston and rods throughout the non-contacting areas of the latter.

2. A piston and rod unit comprising with a piston, a pair of rods disposed parallel to the piston and contacting the peripheral face of the same at diametrically opposed points, and a cross pin projecting through the piston and rods diametrically 45 thereof and tying the same together.

3. A structure as in claim 2, in which the cross pin is of oblong form in cross section with the major axis of such form extending lengthwise of 50 the rods.

WAYNE N. MORGAN.
